(57) **CLAIM**

We claim the ornamental design for a hotspot accessory adapter, as shown and described.

DESCRIPTION

FIG. 1 is a top perspective view of a hotspot accessory adapter in accordance with our new design, shown in a position for use within its environment;

FIG. 2 is an exploded top perspective view thereof, shown with its environment;

FIG. 3 is another top perspective view thereof, shown in an alternate position within its environment;

FIG. 4 is a top view thereof;

FIG. 5 is a bottom view thereof;

FIG. 6 is a first side view thereof, the opposite side being identical; and

FIG. 7 is a second side view thereof, the opposite side being identical.

FIG. 8 is a top perspective view of a hotspot accessory adapter in accordance with a second embodiment of our new design, the remaining views are identical to that of the first embodiment; and,

FIG. 9 is a bottom perspective view of the hotspot accessory adapter in accordance with our new design for both embodiments.

The dashed lines depict unclaimed environment only and form no part of the claimed design.

1 Claim, 8 Drawing Sheets
